CLAIM

I claim the ornamental design for a game feeder, as shown and described.

DESCRIPTION

FIG. 1 is an elevated front perspective view of a game feeder in accordance with the present design;

FIG. 2 is a front elevation view thereof;

FIG. 3 is a rear elevation view thereof;

FIG. 4 is left side elevation view thereof;

FIG. 5 is a right side elevation view thereof;

FIG. 6 is a top plan view thereof;

FIG. 7 is a bottom plan view thereof; and,

FIG. 8 is an elevated front perspective view of the game feeder in folded mode configuration for transport or storage.
